ISOQUINOLINE COMPOUNDS AND DERIVATIVES THEREOF

Max Bockmühl and Hans Hermann, Frankfort-on-the-Main-Hochst, Germany, assignors to Winthrop Chemical Company, Inc., New York, N. Y., a corporation of New York

No Drawing. Application December 9, 1937, Serial No. 178,883. In Germany December 12, 1936

4 Claims. (Cl. 260—289)

The present invention relates to isoquinoline compounds containing a hydroaromatic radical in 1-position and to the derivatives thereof hydrogenated in the pyridine nucleus.

It is known that isoquinoline compounds having an organic radical in 1-position and the derivatives thereof hydrogenated in the pyridine ring are valuable physiologically active substances which in part are used in medicine.

Isoquinoline compounds containing a hydroaromatic radical in 1-position have hitherto been unknown.

Now we have found that isoquinoline compounds of the latter kind are obtained by condensing, according to methods known for making isoquinoline compounds substituted in 1-position, an aromatic-aliphatic 1-aryl-2-aminoethane compound with a hydroaromatic acid, acid derivative or aldehyde, subjecting the condensation product so obtained to ring closure, advantageously after hydrogenation, and, if necessary, hydrogenating or dehydrogenating the isoquinoline compound so obtained. When starting, for instance, from aromatic-aliphatic amino-alcohols of the formula $R-CHOH-CH_2-NH_2$ (wherein R stands for aryl) or the ethers or homologues or analogues thereof, the corresponding amides are obtained by condensation with hexahydrobenzoic acids (chlorides, esters, etc.), which amides are converted into the 1-cyclohexyl-isoquinoline derivatives by means of acid condensing agents such as phosphorus oxychloride or the like. When starting from the corresponding amino-ketones the ketone-group is hydrogenated, preferably after the formation of the amide. When starting from aromatic-aliphatic amines of the formula

(wherein R stands for aryl) in carrying out the invention, the corresponding 3:4-dihydro-isoquinoline compounds are obtained which may be hydrogenated to the corresponding tetrahydro-compounds or dehydrogenated to the isoquinoline compounds. With the same good result the new isoquinoline derivatives may also be produced according to one of the processes known for obtaining isoquinolines, for instance, by condensing the aforesaid amines with hydroaromatic aldehydes and subjecting the condensation products thus obtained to ring closure to form the corresponding tetrahydro-isoquinoline which, if necessary, may be dehydrogenated in the pyridine nucleus. Instead of using saturated hydroaromatic acids

the process of the present invention may be carried out with acids which are only partially hydrogenated in the nucleus. In this case it may be advantageous to produce the nuclear double linkage subsequently by starting, for instance, from hexahydro-hydroxy-acids and splitting off water from the condensation products.

With the same or similar result the process of the present invention may also be carried out with hydroaromatic acids in which an aliphatic residue is contained between the nucleus and the carboxyl group. Thus, for instance, from cyclohexylacetic acid the corresponding hexahydrobenzyl-isoquinoline compounds are obtained.

The new compounds have the following general formula:

5

10

15

20

wherein both 'X's jointly stand for one of the following groupings:

25

30

wherein R stands for cyclohexyl, cyclohexenyl or hexahydrobenzyl, Y stands for hydrogen, alkyl or cyclohexyl, Z1 and Z2 each stand for hydrogen, hydroxy, alkoxy, or Z1 and Z2 together stand for alkyleneedioxy.

The compounds are solid colorless substances which are readily soluble in benzene, chloroform, ether and petroleum ether.

The new products have valuable characteristics from various aspects:

Thus the 1-cyclohexyl-6:7-dimethoxyisoquinoline is twice as effective spasmolitically as papaverine. The 1-cyclohexenyl- Δ 1-6:7-dimethoxyisoquinoline has in the gall-bladder twice the activity and in the intestines four times the activity of papaverine. The 1-cyclohexyl-6:7-dimethoxydihydro(3:4)-isoquinoline has a strong central-stimulating effect.

It may furthermore be noted that the hydrogenated acids used as parent materials are in part very readily accessible and cheap parent materials for the production of isoquinoline compounds of the type named, whereas the alkoxyphenylacetic acids required for the production of

35

40

45

50

55

papaverine and its homologues can only be made in a complicated manner. The compounds obtainable according to the present invention are intended for use in part as pharmaceutical products and in part for the manufacture of other remedies.

The following examples serve to illustrate the invention, but they are not intended to limit it thereto:—

10

1. *1-cyclohexyl-6:7-dimethoxyisoquinoline*

32.1 grams ($=\frac{1}{10}$ mol.) of N-hexahydrobenzoyl- β -(3:4-dimethoxyphenyl)- β -methoxyethylamine (melting point 105° C. to 106° C.) are heated for 15 2½ hours in a reflux apparatus in 300 cc. of dry chloroform with 50 cc. of phosphorus oxychloride. The solvent is then distilled under reduced pressure and the residue is repeatedly extracted with 20 hot water containing hydrochloric acid. The acid solution is extracted with ether in order to remove smearable constituents, then rendered alkaline by means of alkali solution and again extracted with ether. After the ethereal extract has 25 been dried with potassium carbonate and the ether has been evaporated the 1-cyclohexyl-6:7-dimethoxyisoquinoline of the formula

30

35

crystallises. It may be purified by repeated recrystallisation from petroleum ether or ether, or 40 better by distillation under a highly reduced pressure. It boils under a pressure of 0.04 millimeter at a temperature of 176° C. to 180° C. The melting point is 106.5° C. to 107° C.

45 The acid amide used as parent material can be obtained by causing 2 molecular proportions of 3:4-dimethoxyphenyl-methoxyethylamine to react with 1 molecular proportion of hexahydrobenzoyl chloride in dry benzene.

50 2. *1-Δ1-cyclohexenyl-6:7-dimethoxyisoquinoline*

(a) 31.9 grams ($=\frac{1}{10}$ mol.) of N-tetrahydrobenzoyl- β -(3:4-dimethoxyphenyl)- β -methoxyethylamine (melting point 80° C. to 81° C.) in 300 cc. 55 of dry chloroform are boiled for 2 hours with 50 cc. of phosphorus oxychloride and the product is worked up as described in Example 1. The base of the formula

60

65

70 distils at 165° C. to 170° C. under a pressure of 0.02 millimeter; its melting point is 107° C. to 109° C.

(b) 33.7 grams ($=\frac{1}{10}$ mol.) of N-hexahydro-2-75 hydroxybenzoyl- β -(3:4-dimethoxyphenyl)- β -methoxyethylamine (melting point 123° C. to

124° C. obtainable by heating for 6 hours to 138° C. to 140° C. equimolecular quantities of hexahydrobenzoylic acid methyl ester and β -(3:4-dimethoxyphenyl)- β -methoxyethylamine are dissolved in 300 cc. of chloroform and 70 cc. of phosphorus oxychloride are introduced into the boiling solution drop by drop during 2 hours. When the introduction is complete, the whole is heated for half an hour longer and worked up as indicated under (a).

5

10

3. *1-hexahydrobenzyl-6:7-dimethoxyisoquinoline*

33.5 grams ($=\frac{1}{10}$ mol.) of N-hexahydrophenyl-acetyl- β -(3:4-dimethoxyphenyl)- β -methoxyethylamine (melting point 99° C. to 100° C.) in 15 250 cc. of xylene are boiled for half an hour with 70 cc. of phosphorus oxychloride. After working up in the usual manner and recrystallisation from petroleum ether there is obtained the compound of the following formula:

20

25

30

The melting point of the product is 104° C. to 105° C.

35

4. *1-cyclohexyl-6:7-diethoxyisoquinoline*

36.3 grams ($=\frac{1}{10}$ mol.) of N-hexahydrobenzoyl- β -(3:4-diethoxyphenyl)- β -ethoxyethylamine (melting point 109° C. to 110.5° C.) in 250 cc. 40 of benzene are boiled for 3 hours with 50 cc. of phosphorus oxychloride. After recrystallisation three times from petroleum ether and once from ether the compound of the formula

40

45

50

55

has a melting point of 83° C. to 84° C.

5. *1-cyclohexyl-6:7-ethylenedioxyisoquinoline*

10.3 grams of N-hexahydrobenzoyl- β -(3:4-ethylenedioxyphenyl)- β -methoxyethylamine in 60 100 cc. of dry benzene are heated for 3 hours in a reflux apparatus with 15 cc. of phosphorus oxychloride. The base of the following formula

65

70

70 melts at 97° C. to 98° C.

75

The parent material used in this example can be made in the following manner: By condensing 3:4-ethylenedioxybenzaldehyde with nitromethane the 3:4-ethylenedioxynitrostyrol melting at 151° C. to 152° C. is obtained. Methyl alcohol is added to this product by the method of Rosenmund "Berichte der Deutschen Chemischen Gesellschaft", vol. 46, page 1034 (1913), to produce the β -(3:4-ethylenedioxynaphenyl)- β -methoxynitroethane which melts at 89° C. to 90° C. and from this compound the desired ether base is obtained by catalytic reduction. It boils at 151° C. to 153° C. under a pressure of 4 millimeters.

15 6. 1-cyclohexyl-3:4-dihydro-6:7-dimethoxyisoquinoline

11.5 grams of N-hexahydrobenzoyl-3:4-dimethoxyphenylethylamine (melting point 111° C. to 111.5° C.) in 55 cc. of dry chloroform are boiled for 5 hours with 16 cc. of phosphorus oxychloride and the product is worked up as described in Example 1. The product of the formula

35 so obtained melts at 79.5° C. to 80° C. after recrystallization three times from petroleum ether.

7. 1-cyclohexyl-3:4-dihydro-6:7-ethylenedioxisoquinoline

40 9 grams of N-hexahydrobenzoylethyleneoxyphenylethylamine (melting point 129.5° C.) in 50 cc. of dry chloroform are boiled for 5 hours in a reflux apparatus with 12 cc. of phosphorus oxychloride. There is obtained the product of the 45 formula

50 which melts at 106.5° C. to 107° C. when twice recrystallized from ether.

60 The 3:4-ethylenedioxynaphenylethylamine may be obtained from the corresponding styrene by catalytic reduction according to Kindler, "Annalen", vol. 511, page 209 (1935). It boils at 167° C. to 169° C. under a pressure of 14 millimeters.

8. 1-cyclohexyl-3:4-dihydro-6-methoxy-7-hydroxyisoquinoline

64 grams of N-hexahydrobenzoyl- β -(3-methoxy-4-hydroxyphenyl)-ethylamine (melting point 123.5° C. to 124.5° C.) in 33 cc. of chloroform are heated for 2½ hours in a reflux apparatus with 8 cc. of phosphorus oxychloride. The solvent is evaporated under reduced pressure and the residue is taken up with hot water,

filtered from undissolved resin and the solution is then extracted with benzene in order to remove non-basic constituents. The aqueous solution is then rendered alkaline while cooling by means of concentrated potassium carbonate solution and extracted with ether. After drying for a short time with potassium carbonate the hydrochloride of the desired base is precipitated by means of alcoholic hydrochloric acid. This salt which is first obtained in a smearable state is obtained in a powdered state by repeated trituration alternately with ether and petroleum ether; it may be recrystallized from a mixture of isopropyl alcohol and acetone. The compound has the formula

15 and a melting point of 148° C. to 149° C. The substance yields a dirty green color with ferric chloride solution.

9. 1-cyclohexyl-6:7-dimethoxyisoquinoline

10 grams of 1-cyclohexyl-3:4-dihydro-6:7-dimethoxyisoquinoline (cf. Example 6) in 50 cc. of xylene are boiled in a reflux apparatus with 1 gram of palladium black until the evolution of hydrogen has ceased, which is the case after about 4 hours. The whole is then filtered from the catalyst and the solvent is expelled under reduced pressure; there is obtained the product of the 40 melting point of 106.5° C. to 107° C. described in Example 1.

10. 1-cyclohexyl-1:2:3:4-tetrahydro-6:7-dimethoxyisoquinoline

(a) 13.1 grams of 1-cyclohexyl-3:4-dihydro-6:7-dimethoxyisoquinoline (cf. Example 6), in a pure state, are hydrogenated with palladium at 50° C. in 50 cc. of N-hydrochloric acid and 300 cc. of water. After about 4 hours the absorption of hydrogen is complete. The whole is then filtered from the catalyst and concentrated under reduced pressure, whereby the hydrochloride of the new compound of the formula

55 crystallizes. It may be purified by recrystallization from alcohol and then melts at 228° C. to 230° C. after previously sintering at 150° C. to 160° C.

(b) 13.6 grams of 1-cyclohexyl-6:7-dimethoxyisoquinoline are hydrogenated with nickel in 50 cc. of N-hydrochloric acid and 300 cc. of water at 130° C. and under pressure. After having been worked up as described under (a) there is like-

wise obtained the compound of the formula given above, which melts at 228° C. to 230° C.

11. 1- Δ 1-cyclohexenyl-3-methyl-6.7-dimethoxyisoquinoline

6.1 grams of N- Δ 1-tetrahydrobenzoyl-(3:4-dimethoxyphenyl)-2-aminopropanol (melting point 134° C. to 135° C.) in 60 cc. of chloroform are boiled for 4 hours in a reflux apparatus with 12 cc. of phosphorus oxychloride. After working up in the usual manner the base is distilled under a highly reduced pressure. It boils at 172° C. to 175° C. under 0.01 millimeter pressure. The distilled product is taken up in ether and from this solution the hydrochloride of the base is precipitated by means of ethereal hydrochloric acid. After triturating several times with dry acetone the salt of the base of the formula

20

25

30 is obtained in a solid form. It melts at 207° C. to 208° C. after recrystallisation from a mixture of isopropyl alcohol and acetone.

12. 1- Δ 1-cyclohexenyl-3-cyclohexyl-6.7-dimethoxyisoquinoline

2.4 grams of N-tetrahydrobenzoyl- β -(3:4-dimethoxyphenyl)- β -hydroxy- α -cyclohexylethylamine (melting point 158° C. to 159° C.) in 20 cc. of dry benzene are boiled for 4 hours with 5 cc. of phosphorus oxychloride. After working up in the usual manner the crude base is dissolved in absolute ether and the hydrochloride of the base of the formula

45

50

55

is precipitated therefrom by means of ethereal hydrochloric acid.

The 3:4-dimethoxyphenylhydroxycyclohexyl-ethylamine used as parent material may be prepared in the following manner:

From veratrol and hexahydrophenylacetyl chloride there is obtained according to the Friedel-Crafts reaction the 3:4-dimethoxyphenylhexahydrobenzyl ketone of melting point 52° C. to 53° C. This yields with butyl nitrite an isonitroso-compound of melting point of 145° C. to 147° C., from which the desired amine may be prepared with palladium and hydrogen in an alcoholic hydrochloric acid solution; the hydrochloride of the amine melts at 208° C. to 210° C.

13. 1-cyclohexyl-6.7-dimethoxyisoquinoline

15 grams of 1-cyclohexyl-6.7-dimethoxytetrahydroquinoline are heated for 15 hours in a reflux

apparatus with 70 cc. of xylene and 2 grams of palladium. After the reaction product has been worked up and redissolved from ether there is obtained the 1-cyclohexyl-6.7-dimethoxyisoquinoline described in Example 1 which melts at 106.5° C. to 107° C.

14. 1-cyclohexyl-3:4-dihydroisoquinoline

28.4 grams of hexahydrobenzoic acid methyl-ester and 31.4 grams of phenylethylamine are 10 kept for 8 hours at a temperature of 180° C. to 190° C. The reaction product is dissolved in benzene and shaken out with dilute hydrochloric acid. After partially distilling the benzene and adding petroleum ether crystals are precipitated 15 which melt at 93° C. to 94° C. when recrystallized from hexahydrobenzene.

10 grams of the amide so obtained are boiled 20 for 7 hours in a reflux apparatus with 50 cc. of xylene and 15 cc. of phosphorus oxychloride. After distilling the solvent the residue is treated with ether and the ethereal solution is shaken with hydrochloric acid. The isoquinoline product is separated from the hydrochloric acid solution by means of alkali. The base of the formula

30 distils at 145° C. to 150° C. under 4.5 millimeters 40 pressure. The hydrochloride has a melting point of 146° C. to 147° C.

We claim:

1. As new compositions of matter the compounds of the following formula:

50 wherein both X's jointly stand for one of the groupings selected from the group consisting of

55 R being a member of the group consisting of cyclohexyl, cyclohexenyl and hexahydrobenzyl, and Y being a member of the group consisting of hydrogen, alkyl and cyclohexyl, Z1 and Z2 each stand for a member of the group consisting of hydrogen, hydroxy and alkoxy, and compounds of the above general formula, wherein both X's have the same meaning as given above and Z1 and Z2 jointly stand for alkylendioxy, said compounds being solid colorless substances which are readily soluble in benzene, chloroform, ether and petroleum ether.

2. As a new composition of matter the compound of the following formula:

10

15

said compound being a solid colorless substance which is readily soluble in benzene, chloroform, ether and petroleum ether.

3. As a new composition of matter the compound of the following formula:

25

said compound being a solid colorless substance which is readily soluble in benzene, chloroform, ether and petroleum ether.

4. As a new composition of matter the compound of the following formula:

5

15

20

said compound being a solid colorless substance which is readily soluble in benzene, chloroform, ether and petroleum ether.

MAX BOCKMÜHL.

HANS HERMANN. 25
